UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF NEW JERSEY.

ANTITELESCOPIC CAR CONSTRUCTION.

1,140,059.

Specification of Letters Patent.

Patented May 18, 1915.

Application filed November 8, 1912. Serial No. 730,223.

To all whom it may concern:

Be it known that I, HARRY M. PFLAGER, a citizen of the United States, residing at St. Louis, Missouri, have invented a certain new 5 and useful Improvement in Antitelescopic Car Construction, of which the following is a full, clear, and exact description, such as will enable others skilled in the art to which it appertains to make and use the same, reference being had to the accompanying drawings, forming part of this specification, in which—

Figure 1 is a plan view showing parts of car underframes equipped with my improved 15 anti-telescopic means for preventing one car from mounting another in case of collisions. Fig. 2 is a vertical section taken approximately on the line 2—2 of Fig. 1 and showing the draw-bar and coupler head as contemplated by my improved invention in elevation. Fig. 3 is a front elevational view of 20 the draw-bar and coupler head and the support from the underframe therefor.

My invention relates to new and useful 25 improvements in railway car construction, the principal object of my invention being to provide simple, strong and durable means for preventing one car from mounting another, and therefore rendering the cars anti- 30 telescopic in case of collisions. To accomplish this object I provide an extra strong, heavy draw-bar having a coupler head provided with a coupling face of the standard M. C. B. contour, and arrange on one side of 35 the axis of said head and draw-bar a single, forwardly projecting member or horn, and on the opposite side of the head a pair of members or projections spaced apart to receive the single member or horn of the opposite coupler. By so constructing the coupler heads the same are interlocked when coupled so as to prevent undue vertical movement 40 of one coupler head relative to the other, thereby preventing one car from mounting and 45 telescoping another in case of collisions. It is contemplated that while these interlocking members shall operate to prevent excessive relative vertical movement of coupled heads, there shall be sufficient vertical play between 50 them to permit the normal amount of relative vertical movement incident to ordinary use of the cars.

To further guard against excessive vertical movement of one coupler head relative 55 to another and to prevent one car from

mounting and telescoping another in case of collisions I provide an extra strong and heavy draw-bar which is preferably tapered gradually from the coupler head to its rear end, and provide means for supporting said 60 draw-bar at two different points beneath the underframe. One extra strong support is preferably arranged beneath the buffering sill or the outer end of the car and the other support is arranged at a point a suitable dis- 65 tance to the rear of the first mentioned support. The extra strong and heavy draw-bar is connected to and supported from the car in a strong and substantial manner, which arrangement, together with the interlocking 70 coupler heads, is effective in maintaining the cars in proper horizontal relation with respect to each other in case there is any tendency of one car to rise to an abnormal height with respect to the adjacent car, and 75 at the same time the couplers operate freely in the usual manner under normal conditions.

To the above purposes my invention consists in certain novel features of construction and arrangement of parts hereinafter more 80 fully described and claimed.

Referring by numerals to the accompanying drawings, 1 designates a portion of the car underframe and 2 the end sill, which parts in the present instance are shown 85 formed integral.

The draw-bar 3 as contemplated by my invention is made extra heavy and strong, and the body thereof is preferably tapered gradually from the coupler head to the rear 90 end, which construction avoids the shoulders which are usually formed between the coupler head and the body of the draw-bar. The forward portion of this draw-bar is supported in its usual position beneath the 95 underframe and end sill by a suitable carrier 4, the same being preferably attached to and depending from the end sill or underframe and being connected thereto pref- 100 erably by means of pins 4^a. This supported carrier 4 is made extra strong and heavy in order to effectually withstand stresses which may be imparted thereto by the draw-bar in case there is any tendency of one car to mount and telescope another. 105

The rear end of the draw-bar is supported by a suitable carrier 5 that is connected to the underframe 1 at a point a suitable distance to the rear of the support 4. Formed integral with or fixed to the for- 110

ward end of the draw-bar is a coupler head 6 having a coupling face of standard M. C. B. contour, and arranged in said head in the usual manner is a knuckle 7.

- 5 Formed integral with or fixed to the jaw of the coupler head that carries the knuckle 7 is a pair of laterally projecting members 8 that are spaced a suitable distance apart so that they occupy planes above and below 10 the horizontal plane occupied by the center of the coupler head and draw-bar, and formed integral with the opposite jaw of the coupler head is a forwardly projecting, outwardly curved member or horn 9. This 15 member or horn occupies a horizontal plane midway between the top and bottom of the head, and when two heads are properly coupled, the forward portion of said member or horn occupies a position between the 20 members 8 of the opposite coupler. The space between the members 8 is ample to permit such vertical movement as will occur between the coupler heads under ordinary conditions, but, if one head should be 25 raised to an abnormal height with respect to the opposite head, the interlocked members 9 and 8 will limit such vertical movement. By thus interlocking the coupler heads while the same are coupled to each 30 other and by providing strong, substantial supports for the draw-bar at two points beneath the underframe, extreme vertical movement of one coupler head relative to the other will be prevented and consequently 35 one car will be prevented from mounting and telescoping another in case of collisions.
- An anti-telescopic car construction as contemplated by my invention is comparatively simple, provides an extra strong and efficient 40 connection between cars, permits the coupler heads to operate freely under normal conditions and at the same time effectually pre-

vents one car from moving vertically to an abnormal degree relative to another, and consequently prevents one car from mounting and telescoping another as a result of 45 collisions.

It will be readily understood that minor changes in the construction of the various parts of my improved anti-telescopic car construction can be made and substituted for those herein shown and described without departing from the spirit of my invention, the scope of which is set forth in the 50 appended claim.

I claim:

In an anti-telescopic car construction, a coupler head having a concentrically disposed lug extending forwardly from one side, the thickness of which lug is substantially less than the height of the coupler head, a pair of concentrically disposed lugs extending from the opposite side of said coupler head, the space between which last mentioned pair of lugs is substantially greater than the height of the first mentioned lug, said space being free and open to permit free horizontal movement of the interengaging single lug when a pair of the 60 heads are coupled, the lugs of said pair being respectively above and below the horizontal plane of the single opposing lug, the concentricity of said lugs being described from the axis of movement of the coupler-head relative to its companion when in 65 operative position.

In testimony whereof I hereunto affix my signature in the presence of two witnesses, this 22nd day of October, 1912.

HARRY M. PFLAGER.
